UNITED STATES PATENT OFFICE.

JOHN NAVARA, OF CHICAGO, ILLINOIS.

RAILWAY-SKATE.

1,260,431.

Specification of Letters Patent. Patented Mar. 26, 1918.

Application filed August 8, 1917. Serial No. 185,021.

To all whom it may concern:

Be it known that I, JOHN NAVARA, a citizen of the United States, and a resident of the city of Chicago, county of Cook, and 5 State of Illinois, have invented certain new and useful Improvements in Railway-Skates, of which the following is a specification.

My invention relates to railway skates, 10 that is to devices adapted for emergency use upon the rail of a railway track for engagement by the wheels of a free running railway car to effect stopping of the car.

In using a device of this character, the 15 same is arranged on the track rail ahead of the car to be stopped, and as the car approaches the device the front wheel of one side of the car will ride up onto the skate, the latter sliding upon the rail and through 20 frictional engagement therewith gradually bringing the car to a stop. In order to hold the skate onto the rail, guides are necessary which engage with opposite sides of the ball of the rail. In skates in use at the present 25 time these guides are stationary and when a skate is carried past a frog or the like where a groove is provided only at the inner side of the rail for the accommodation of the flange of the car wheel, the stationary guide 30 at the outer side of the rail meets an obstruction, and is either broken off or causes breakage of some other part of the device.

It is the object of this invention to provide 35 a skate in which movable guides are provided and wherein the guide engaging with the outer side of the rail will be automatically elevated to a position out of engagement with the rail or above the upper surface thereof upon engagement of the skate by a 40 car wheel, thus obviating the objection to the use of stationary guides as above pointed out. A further object is the production of a device as mentioned which will be of durable and economical construction, and efficient in 45 use. Other objects will appear hereinafter.

The invention consists in the combinations and arrangements of parts hereinafter described and claimed.

The invention will be best understood by 50 reference to the accompanying drawings forming a part of this specification, and in which,

Figure 1 is a top plan view of a railway 55 skate embodying the invention,
Fig. 2, a side elevation thereof,

Fig. 3, an end elevation as seen from the front end,

Fig. 4, an end elevation of the device as seen from the rear end,

Fig. 5, a sectional view illustrating the 60 movement of the guides when the device is engaged by a car wheel, and

Fig. 6, a fragmentary perspective view illustrating the means for automatically elevating the guide members. 65

The preferred form of construction as illustrated in the drawings, comprises an elongated body 10 the underside of which is flat and adapted for engagement with a conventional rail A. The upper side of the 70 body 10 is gradually inclined upwardly from one end, the arrangement being such that a car wheel traveling toward the front end of the device, will ride up onto the body 10, so that the weight of the load will be borne 75 upon the body 10 which in turn will be caused to slide along the rail as will be readily understood.

Formed upon said body 10 at the lower edge thereof are laterally projecting flanges 80 11 in which are formed slots 12 which are slidably engaged by vertically movable guide members 13 which are adapted to project below the device for engagement with opposite sides of the ball of 85 the rail in order to hold the device in position thereon, as will be readily understood. The guide members 13 are locked to the member 10 by means of a transversely extending pin 14 which passes through elongated slots 90 15 provided in said guide members which permit of the desired vertical movement of the same.

The guide members at opposite sides of the body 10 are operatively connected by means 95 of a sort of yoke or lever 16 which is rockingly mounted midway its ends upon a supporting bar or rod 17 having its ends suitably mounted in body 10. The respective ends of the member 16 engage with notches 100 18 formed in the guide members 13, the arrangement being such that when one of said guide members is depressed, the other will be elevated, as clearly seen in Fig. 5.

Formed at the upper edge of each of the 105 guide members 13 is a laterally projecting flange 19 adapted for engagement by the flange B of a car wheel C, as clearly seen in Fig. 5, so that the flange of a car wheel resting upon the body 10 will engage with 110

and depress one of the flanges 19 and hence the corresponding member 13 with the effect of simultaneously effecting elevation of the guide member 13 at the opposite side of the device. At the rearward side of the device is provided an angularly and laterally projecting member 20 adapted for engagement by the wheel of a car coming from the other direction to effect derailment of the device. 5 that is throwing of the same from the rail to one side where the same will offer no obstruction to the car and be itself uninjured.

With a construction as set forth then, it will be seen that in using the device, it is 15 only necessary for the same to be placed upon one of the rails of the track in front of the car which it is desired to stop. When the device is thus placed both of the guide members 13, which normally project below 20 the body 10, as seen in Figs. 3 and 4, will engage with the opposite sides of the rail and serve to properly center the device upon the rail. As the car approaches, the front wheel at one side of the same will 25 ride up onto the body 10 of the device causing sliding of the latter along the rail, the frictional contact of said body with the rail gradually bringing the car to a stop. In this engagement of the car wheel with the 30 device, the flange of the car wheel will effect depression of the guide member at the inner side of the rail, and consequently elevation of the guide member at the outer side of the rail, so that in the event of a frog 35 or other device obstructing passage along the outer edge of the rail being passed, the outermost guide member will be in a position to avoid contact therewith. The opposite sides of the device are symmetrical, 40 making it possible to use the same upon either rail of the track.

While I have illustrated and described the preferred form of construction for carrying my invention into effect, this is capable of 45 variation and modification without departing from the spirit of the invention. I, therefore, do not wish to be limited to the details of construction set forth, but desire to avail myself of such variations and modifications as come within the scope of the 50 appended claims.

Having described my invention what I claim as new and desire to secure by Letters Patent is:

55 1. A railway skate comprising an elongated body adapted to rest upon a rail, the upper side of said body gradually rising from the upper surface of the rail for engagement by the wheel of a car on said rail; 60 vertically movable guide members on said body adapted for engagement with the opposite sides of the rail; and means for elevating one of said guide members upon engagement of a car wheel with the upper side 65 of said body, substantially as described.

2. A railway skate comprising an elongated body adapted to rest upon a rail, the upper side of said body gradually rising from the upper surface of the rail for engagement by the wheel of a car on said rail; 70 vertically movable guide members on said body adapted for engagement with the opposite sides of the rail; and means operable by a car wheel for effecting elevation of one of said guide members upon engagement of 75 the car wheel with the upper side of said body, substantially as described.

3. A railway skate comprising an elongated body adapted to rest upon a rail, the upper side of said body gradually rising 80 from the upper surface of the rail for engagement by the wheel of a car on said rail; vertically movable guide members on said body adapted for engagement with the opposite sides of the rail; and means for elevating the guide member of the skate engaging with the outer side of the rail upon engagement of a car wheel with the upper side of said body, substantially as described. 85

4. A railway skate comprising an elongated body adapted to rest upon a rail, the upper side of said body gradually rising 90 from the upper surface of the rail for engagement by the wheel of a car on said rail; vertically movable guide flanges carried by 95 said body and adapted to project below the same for engagement with opposite sides of the roller; and means for elevating one of said flanges upon passing of a car wheel into engagement with said body, substantially as described. 100

5. A railway skate comprising an elongated body adapted to rest upon a rail, the upper side of said body gradually rising 105 from the upper surface of the rail for engagement by the wheel of a car on said rail; vertically movable guide members on said body adapted for engagement with the opposite sides of the rail; and means for elevating one of said guide members upon 110 engagement of a car wheel with the upper side of said body, said means comprising a 115 rockingly mounted member arranged in said body and engaging with said guide members whereby, when one of said guide members is depressed, the other will be elevated, substantially as described.

6. A railway skate comprising an elongated body adapted to rest upon a rail, the upper side of said body gradually rising 120 from the upper surface of the rail for engagement by the wheel of a car on said rail; vertically movable guide members on said body adapted for engagement with the opposite sides of the rail; an operative connection between said guide members whereby, when one is depressed, the other will be elevated from engagement with the rail; and a contact surface on each of said guide members adapted for engagement by the 125 130

flange of a car wheel resting on said body to effect depression of the guide member whose contact surface is engaged, substantially as described.

5 7. A railway skate comprising an elongated body adapted to rest upon a rail, the upper side of said body gradually rising from the upper surface of the rail for engagement by the wheel of a car on said rail; 10 vertically movable guide members on said body adapted for engagement with the opposite sides of the rail; an operative connection between said guide members whereby, when one is depressed, the other will be 15 elevated from engagement with the rail; and a laterally projecting flange on each of said guide members adapted for engagement by the flange of a car wheel resting on said body to effect depression of the guide member whose flange is engaged, substantially as 20 described.

8. A railway skate comprising an elongated body adapted to rest upon a rail, the upper side of said body gradually rising from the upper surface of the rail for engagement by the wheel of a car on said rail; 25 vertically movable guide members on said body adapted for engagement with the opposite sides of the rail; a member rockingly 30 mounted intermediate its ends in said body and having its ends engaging with said guide members whereby, when one of said guide members is depressed, the other will

be elevated to a position above the upper surface of the rail; and a contact surface 35 on each of said guide members adapted for engagement by the flange of a car wheel resting on said body to effect depression of the guide member whose contact surface is engaged, substantially as described. 40

9. A railway skate comprising an elongated body adapted to rest upon a rail, the upper side of said body gradually rising from one end for engagement by a car wheel traveling on the rail; and means at the opposite end of said body adapted for engagement by a car wheel traveling toward the same to effect derailment of said body, substantially as described. 45

10. A railway skate comprising an elongated body adapted to rest upon a rail, the upper side of said body gradually rising from one end for engagement by a car wheel traveling on the rail; and an angularly and laterally projecting member at the opposite 50 end of said body adapted for engagement by a car wheel traveling toward the same to effect derailment of said body, substantially as described. 55

In testimony whereof I have signed my 60 name to this specification in the presence of two subscribing witnesses.

JOHN NAVARA.
